(57) **CLAIM**

The ornamental design for a cordless impact tool, as shown and described.

DESCRIPTION

FIG. 1 is a front perspective view of a cordless impact tool, showing our new design;

FIG. 2 is a rear perspective view thereof;

FIG. 3 is a side view thereof;

FIG. 4 is a side view thereof, opposite that shown in FIG. 3;

FIG. 5 is a front end view thereof;

FIG. 6 is a rear end view thereof, opposite that shown in FIG. 5;

FIG. 7 is a top plan view thereof; and,

FIG. 8 is a bottom plan view thereof, opposite that shown in FIG. 7.

The broken lines shown herein are for illustrative purposes only and form no part of the claimed design.

1 Claim, 6 Drawing Sheets

FIG. 1

FIG. 2

FIG. 3

FIG. 4

FIG. 5

FIG. 6

FIG. 7

FIG. 8
